UNITED STATES PATENT OFFICE.

FELIX RIESENBERG, OF TUCKAHOE, NEW YORK.

ROPE STRUCTURE.

Application filed January 10, 1923. Serial No. 611,898.

To all whom it may concern:

Be it known that I, FELIX RIESENBERG, a citizen of the United States, and a resident of Tuckahoe, in the county of Westchester and State of New York, have invented a new and Improved Rope Structure, of which the following is a full, clear, and exact description.

The present invention relates to new and useful improvements in cordage, and it pertains more particularly to a new and improved method of making rope.

The application is a continuation in part of the application Serial No. 566,240, filed 15 January 6, 1922.

It has been found by experiment that in the larger sizes of rope the great increase in the number of yarns comprising each strand of the rope results in a loss of the 20 effective strength of the individual yarns.

It has also been found that as the rope increases in size the strength per pound of 25 yarn used per foot of rope gradually decreases as the diameter of the rope increases.

This is due to the fact that where a great 30 multiplicity of yarns are employed, all are not of the same length and hence not under the same tension, also certain of the strands are subjected to strain prior to others, and, 35 therefore, the several strands cannot perform their functions simultaneously.

It is one of the primary objects of the invention to provide a rope in which a more even distribution of the work performed by 40 the individual elements of which the rope is formed may be had.

It is a further object of the invention to 45 form a rope in which greater strength above certain predetermined sizes may be had than is possible in ropes of corresponding sizes manufactured in the form common to the manufacture of cordage at the present time.

It is a further object of the invention to obtain greater flexibility in the larger sizes 50 of rope.

It is a further object of the invention to provide a new and improved strand for ropes, which strand may be employed in the manufacture of three, four or more stranded

55 rope.

It is a further object of the invention to construct a rope in such a manner that the internal friction thereof will be reduced.

It is a further object of the invention to so

construct the rope that the same may be positively identified regardless of the use and abuse to which it may have been subjected even after a considerable lapse of time after the manufacture of the rope.

With the above and other objects in view, reference is had to the accompanying drawings, in which

Figure 1 illustrates a rope constructed in accordance with the present invention shown in elevation, the rope itself being partially frayed as is also one of the strands of the rope, and

Figure 2 is a transverse sectional view of one of the strands of the rope.

Referring more particularly to the drawings, the reference character 11 designates the rope and said rope comprises in the present illustration three strands 12. While the illustration shows a rope comprising three strands, it is obvious that any number 75 of strands common in the manufacture of rope may be employed.

In carrying out the invention, each of the strands 12 comprises a core 13 enclosed in a wrapping of yarns 14. The cores 13 are 80 each composed of a plurality of elements 15 and said elements 15 are intertwined to form a single unit. It will be noted that the intertwined strands are in close contact along the axial line of the core they constitute. 85

While in the present instance the cores 13 are shown as consisting of three elements, it is obvious that two or more elements may be employed in the manufacture of the core when so desired. It will be noted, therefore, 90 that in the present instance a double layer of yarn 14 is employed as around each of the cores 13, but it is obvious that yarns 14 may be employed in a single layer or in more than two layers, as desired. 95

In the manufacture of very large rope where strands of large diameter are employed, in order to round out the core 13 employed, which would necessarily be large, the well-known process of worming between 100 the elements may be resorted to in order that said core may be more effectively rounded out.

From the foregoing it is apparent that the present invention provides a rope which is 105 easily laid and when finished is smooth and easily handled. Furthermore, by constructing a rope in accordance with this principle,

greater strength is had than is possible where the individual strands 12 are formed from yarns as is the common practice.

I claim:

- 5 A composite rope wherein the tensile strength of the rope is the combined strength of its several elements, said rope comprising a plurality of strands twisted together and each strand consisting of a core 10 composed of vegetable fibre elements intertwined and laid and resting permanently in
- 15 element along the axial line of the core, and a protective covering also of vegetable fibre placed helically about the vegetable fibre core, the tensile strength of the covering constituting a material part of the total tensile strength of the rope and the core and the covering cooperating toward increasing the flexibility of the rope, as and for the purpose set forth.

FELIX RIESENBERG.
